CONTROL MEANS FOR INK FOUNTAINS

Herbert R. Leedy and Frank A. Myers, Cleveland,
Ohio, assignors to Aids Development Co., Inc.,
Cleveland, Ohio, a corporation of Ohio

Application March 29, 1951, Serial No. 218,217

5 Claims. (Cl. 116—124)

1

This invention relates to printing presses, and more particularly to the ink feed portions thereof.

More particularly, the invention pertains to printing presses which include an ink fountain consisting essentially of a roller and a blade cooperative therewith to provide a slight gap therebetween, extending longitudinally of the roller at the point of the V formed between the roller surface and the blade. Through such gap the ink is fed from the V, by progression of the fountain roller in the operation of the press, through a suitable series or system of intermediate, inter-contacting rollers until the ink is eventually applied to the printing medium, by one or more "form rollers" which constitute the last of such series.

The type of printing medium here contemplated may be either relief, as in a letter press, or planographic, as in lithography; and in each event may be either "direct," wherein the material being printed upon is caused to contact the printing medium, or "offset," wherein an intermediate medium receives the ink film from the printing medium and contacts the material being printed upon, for final transfer thereto of the ink.

Thus, the invention is concerned with two known printing media and two methods of ink transfer thereto, in presses of a type employing any combination thereof.

Modern printing, even with highly developed presses of the types under consideration, presents very complex problems of control of the ink applied to the form rollers. The problems are involved by three fundamental variables which must be properly combined to produce a specific printed sheet. These fundamentals are the unit-quantity of ink, which may be heavy or spare; the total-quantity of ink, which may be large or small; and the total-quantity-distribution of ink, which may be uniform or non-uniform. Furthermore, there are a large number of physical, chemical and mechanical variables in the materials used, as well as in the various designs and adjustable motions of the presses themselves.

As a result, achievement of a specific satisfactory combination meeting all of the imposed variables is difficult for even the most skilled press operator, and once attained, it is extremely difficult even for the same operator to maintain satisfactory conditions throughout a press run.

The problems, with their complexities, have been somewhat known in the art, although analysis thereof has been relatively neglected.

The art has heretofore been advanced by

10 customary provision, in a modern press, of means for adjusting the fountain blade previously described, toward and from its fountain roller, to thereby correspondingly adjust the gap through which the ink is fed from the V of the fountain to the fountain roller surface. This has been accomplished by making the fountain blade flexible, and the provision of a row of key screws spaced along the blade, each threaded into an adjacent member of the press frame for fine adjustment therein against the back of the blade by means of a flattened or other head on the screw, so that manipulation of each screw permits individual adjustment of the gap portion thereadjacent.

15 The principal general object of this invention is to provide more specific and precise control of the gap, than has heretofore been available in the art, employing the described pre-existing key screws as part of the means for the purpose.

20 Another object of the invention is to make such provision in the form of attachment easily applied to pre-existing presses, more particularly to the key screws only thereof, and adapted to considerable variation in design of the press to receive the attachment.

25 A further object is to provide that the adjustments attained by the invention be of micrometric character, and effectively visible to the operator.

30 Still another object is to provide that the adjustments once attained, may be recorded for convenient reproduction in subsequent press reruns.

35 And still more objects include that all of the above be accomplished by means of exceedingly simple design, low cost of production, easy operation, and by employment of which wear on ink fountain blade and roller are reduced.

40 Further objects and advantages will be apparent from the following description taken in connection with the accompanying drawings wherein

Fig. 1 is a view in front elevation of a key screw unit embodying the invention;

45 Fig. 2 is a sectional view of the same, as in the plane of line 2—2 of Fig. 1;

Fig. 3 is a rear view of the same;

Fig. 4 is a sectional elevation of pertinent parts of a typical printing press with the unit of Figs. 50 1, 2 and 3 mounted thereon, and thereby indicating the relation therebetween; and

Fig. 5 is a front elevation of the same pertinent parts of the press, showing a pair of units of the device applied thereto.

With reference now to the drawings, and first

to Fig. 4 thereof, 1 is the ink fountain roller of the press, usually of metal, and 2 is the ink fountain blade, of flexible metal; these two parts co-operatively providing the V of the fountain along the lower edge of which ink from the V is fed to the roller, depending on the setting of the blade 2. It will be appreciated that the fountain, including both roller and blade, extend the width of the press; the roller is advanced clockwise, Fig. 4, usually in increments during operation of the press, in which operation there is, along at least a portion of the width of the fountain, a slight feeding gap between roller and blade.

3 indicates an adjacent fixed portion of the press frame in which is threadedly mounted a key screw 4, one end of which, as at 5, bears against the back of the blade 2, adjacent the roller 1, and the other end of which is provided with a head 6 of flattened form as illustrated, or other equivalent form, for the purpose of adjusting the key screw against the blade 2 to control the feeding gap adjacent the key screw.

As will also be appreciated by one familiar with the art, the press is provided with a number of such key screws, spaced closely to each other along a horizontal row, each for adjusting its adjacent portion of the flexible blade 2, in the same manner as described for the screw illustrated in Fig. 4; so that by individual adjustment of all of the key screws the ink feeding gap could be theoretically decreased to zero by bearing the blade 2 against the roller, could be made uniform across the press, or may be varied at different portions thereacross.

With reference now to Figs. 1, 2 and 3 of the drawings, a micrometric unit for mounting on one of the key screws is illustrated.

The unit includes a bushing 7 having a central opening 8 of diameter to fit on the shank portion 4 of a key screw, and having means of securement as by a set screw turned into the threaded opening 9.

The bushing has adjacent its forward end a shouldered bearing to receive a tab member 10, and forwardly therebeyond a calibrated dial 11. The arrangement is such, as appears particularly in Fig. 2, that the bearing between the tab 10 and the bushing 7 permits free relative rotation between these parts, whereas the calibrated member 11 is fixedly secured to the bushing, here indicated both as by flanging of the bushing at 12 and staking at 12a.

The tab 10 extends offset from the bushing 7 beyond the dial 11, and there carries a forwardly facing member such as the disk 13, a portion of which extends closely adjacent the calibrations of the member 11. As here shown, both the member 11 and the member 13 are of disk form arranged with their forward faces in the same plane as indicated in Fig. 2, and in near tangential relation as indicated in Fig. 1; and the disk is mounted by rivets 14.

The front face of the disk 13 bears an index 15 co-operative with the calibrations of the member 11, and also bears insigne means for distinguishing from otherwise similar tab members—as indicated Fig. 1, the numeral "21."

The tab member 10 is provided on its rear face with a spring clip 16 adapted to yieldably receive and retain an anchor member disposed transversely of the unit and extending the width of the ink fountain for interconnection of all of the tab members.

Application of the device to a press will be as follows:

All of the key screws are removed and one of the units applied to each by mounting one of its bushings 7 on the shank 4 of the screw, whereupon all of the screws are replaced.

Then all of the tabs of the units are interconnected by anchor means such as the wire rod 17 inserted in their clip 16. In many presses it is preferable that the tabs be upstanding as illustrated in these drawings, so that the disks 13 are above their calibrated dial 11. However, should the circumstances make it preferable, the tabs may be dependent instead of upstanding in which event the disks 13 are reversed up and down and upper indices 15a, opposite the indices 15, thus located adjacent but below the calibrated members 11. In either event, the insignia numerals on the disks 13, thus appear upright to the operator and, of course, their insignia are such as to easily indicate for each that key screw in the row which it serves, as indicated in Fig. 5.

After the units have been thus mounted and interconnected by the anchor strip or wire 17, all of the key screws are turned inwardly against the blade 2 to similarly bear the blade against the fountain roller. Then, for each unit, its calibrated member 11 with its bushing 7 is rotated to bring the zero of its calibrations opposite the index on its disk 13; and then its bushing 7 is fixedly and permanently secured to the shank 4 on which it is mounted, as by set screw 7a.

Thereafter, the key screws may be backed away from the blade 2 as desired by the operator, dependent upon conditions of the press run, in the usual manner except that now the operator has the benefit of the calibrations and their micrometric effect on the key screws.

Once the key screws have all been set by the operator for the run to best meet the conditions thereof, it will be apparent that the numeral or other insignia of the disks 13 permit the operator to easily record the micrometric setting for each key screw; so that should a rerun subsequently be required, by reference to such record, the operator may reproduce the ink fountain setup, by mere reproduction of the individual key screw settings.

After sufficient prolonged operation to result in appreciable wear on either the roller, the blade or both of the ink fountain, the micrometric means of this invention may be reset at any time, for accurate zero readings by loosening the set screw 7a of the bushing 7, properly adjusting the calibrated members to their indices as necessary, and resecuring the bushings on their key screws by retightening of their set screw.

It is to be noted that the device as illustrated and hereinabove described constitutes principally a set of preassembled units, easily mounted in self-contained assembly on its key screw, and as conveniently produced, shipped and handled prior to its mounting. However, it is not necessary that the tab member be mounted on the bushing 7 of its calibrated member. For example, the tab member could be mounted directly on the key screw and a separate collar or other device secured on the key screw to maintain the tab member adjacent its calibrated member. Such arrangement, however, would unnecessarily add to the mounting operations.

The anchor means need be only a flexible wire of small gauge which may be shipped in coil form.

The specific form of the device illustrated is a preferred one in that it is adapted for immediate attachment to most pre-existing printing

presses. However, certain modifications of the illustrated form may be preferable in some applications.

For example, for some presses it might be preferable to reverse the index and calibrated member relation. Thus the calibrations might be provided on the tab 10 and merely a pointer index secured on the bushing 7, in which case, of course, the index would have its adjusting movement relative to the calibrated member, which latter would be secured against movement by the anchor means.

Also, depending on the location of the row of key screws of a particular press, it might be preferable that the calibrated member, the index or both, be cylindrical or conical in form rather than the flat form herein illustrated.

Also, since a few pre-existing presses already bear numbers designating the key screws, it is not necessary that such numbers be duplicated in the attachment of this invention. Thus, the key screw identifying insignia, such as the numerals 21, 22 herein illustrated, might be omitted. Moreover, if preferred, colors could be substituted for numbers as the insignia for identifying the key screws of the row. Thus, for example, the numbers 5, 10 etc. might be applied only to the 5th, 10th etc. key screws of the row, or only such 5th, 10th etc. key screws of the row might be indicated by colors, and intermediate key screws remain individually without identifying insignia. It will be appreciated that the number of key screws in a given press may be as low as 20, or be more than 60.

We claim:

1. A device for mounting on a fountain-blade-adjusting key screw of a printing press, said device comprising a calibrated member having means for securing to said screw for rotation therewith, a tab member mounted on said calibrated member for relative rotation therebetween coaxial with said screw, said tab member having a face bearing an index for said calibrated member and insigne means for distinguishing from otherwise similar tab members, and said tab member having a portion rearward of said face adapted for connection to a transversely disposed anchor member for coincidental support of said anchor member and securing of said tab member against rotation with said calibrated member.

2. Precision control means for a printing press having an ink fountain blade and a row of key screws for adjustment thereof, said means including, for each of said screws, a calibrated member having means for securing to its screw for rotation therewith, and a tab member mounted on said calibrated member for relative rotation therebetween coaxial with said screw, said tab member having an index for said calibrated member and insigne means for distinguishing said screw from others of said row, and said control means also including anchor means adapted for disposition along said row in supported interconnecting relation with said tab members and

thereby maintain each by the others against rotation during adjustment of its calibrated member.

3. Precision control means for a printing press having an ink fountain blade and a row of key screws for adjustment thereof, said means including, for each of said screws, a calibrated member having means for securing to its screw for rotation therewith, and a tab member mounted on said calibrated member for relative rotation therebetween coaxial with said screw, said tab member having a face bearing an index for said calibrated member and insigne means for distinguishing said screw from others of said row, and resilient clip means rearward of said face adapted to there provide support to an anchor member disposed transversely of said row, said control means also including such anchor member interconnecting the clip means of said tab members to thereby maintain each tab member by the others against rotation during adjustment of its calibrated member.

4. In a printing press having an ink fountain blade in a row of key screws for adjustment thereof: precision control means comprising, for each of said screws, a calibrated member secured to its screw for rotation therewith, and a tab member outstanding beyond said calibrated member, said tab member having an index cooperative with said calibrated member, insigne means for distinguishing said screw from others of said row, and clip means adapted to receive and support a transversely extending wire anchor member inserted therein, said control means also including such wire anchor member interconnecting the clip means of said tab members to maintain them, each by others, in similarly outstanding disposition.

5. Precision control means for a printing press having an ink fountain blade and a row of key screws for adjustment thereof, said means including, for each of said screws, a calibrated member having means for securing to its screw for rotation therewith, and a tab member mounted on said calibrated member for relative rotation therebetween coaxial with said screw, said tab member having a portion offset from said calibrated member and bearing an index for said calibrated member and insigne means for distinguishing said screw from others of said row, said control means also including anchor means for interconnecting said tab members with their offset portions in parallel relation to each other.
